UNITED STATES PATENT OFFICE

2,271,676

DIAPER

Elna Bjornbak, Inglewood, Calif.

Application November 24, 1939, Serial No. 305,974

1 Claim. (Cl. 128—284)

This invention relates to diapers and more especially to improved means for securing the same.

An object of the invention is to provide a simple, practical and efficient article of the character described.

Another object is to provide a diaper which may be secured without the use of pins or similar means of attachment.

A further object is to provide a diaper which may be secured in place more quickly and efficiently than heretofore.

An additional object is to provide a diaper so shaped and constructed that the securing means is readily accessible.

Other objects and advantages will appear and be brought out more fully in the following specification, reference being had to the accompanying drawing, wherein:

Fig. 1 is a view illustrating the invention in use;

Fig. 2 is an open view of the diaper; and

Fig. 3 is an enlarged sectional view taken along line 3—3 of Fig. 2.

Referring more particularly to the drawing, I show a textile piece 5 preferably of soft cotton material or the equivalent having an anterior waist portion 7 and a posterior waist portion 6, the latter being approximately one-half the length of the former, the article having a stitched side edge portion 8. A band 9 is stitched at its

upper and lower edges 10 adjacent the edges of waist portions 6 and 7 and provides a slide for tie straps 11 and 12. Ties 13 are suitably stitched at their end portions 14 to piece 5, and ties 15 are similarly stitched at their end portions 16 in approximately the relative positions shown.

The diaper in use can be clearly seen in Fig. 1. Ties 11 and 12 are secured together, making a complete waist band, and ties 13 and 15 are secured together just above the leg, thus making a complete garment. Inasmuch as no pins or clasps of any kind are necessary, there is no danger of injury to the infant or possibility of swallowing the same. Ties 11 and 12 may be removed from bands 9 for occasional replacement or for washing if desired.

It is to be understood that the foregoing description is illustrative rather than restrictive of the invention, and that changes and modifications may be made without departing from the spirit and scope of the subjoined claim.

Having described my invention, what I claim is:

An article of the character described, having anterior and posterior waist portions, said anterior portion being shorter than said posterior portion, said waist portions each having a hem, a tie slidably positioned in each of said hems, and a plurality of ties secured adjacent the edge portions intermediate said waist portions.

ELNA BJORNBAK.
